SOYBEAN FLAKING MACHINE

Harry Truax, Indianapolis, Ind.

Application October 12, 1939, Serial No. 299,071

2 Claims. (Cl. 83—12)

My present invention relates to improvements in flaking machines and more specifically to the type of machine commonly used in pulverizing or flaking soy beans. Machines of this nature have, heretofore, been rather large and complicated in mechanism resulting in considerable expenditure in the manufacture of such machines.

It is an object of my invention to provide a flaking machine that can be manufactured at a relatively low cost. A further object of my invention is to provide a flaking machine considerably smaller in size than those used at the present time and a machine sufficiently simple in operation that the average farmer can successfully operate it. It is, of course, understood that my present invention can be successfully used for the flaking of produce other than soy beans.

The accompanying drawing illustrates one embodiment of my invention. However, the specific construction of my machine can be varied without overstepping the scope of the appended claims.

In the drawing,

Fig. 1 is a side longitudinal section of my flaking machine;

Fig. 2 a plan view on a smaller scale; and

Fig. 3 a side elevation of the machine.

In the drawing 1 indicates a base mounting of my machine. Mounted on said base, and spaced apart, are bearing mountings 2—2 in which is journalled a shaft 3. A pressure roll 4 is mounted on shaft 3 and is, in turn, surrounded by a somewhat larger and loosely mounted sleeve 5. A second cooperating roll 6 is mounted in bearing blocks 7—7 parallel to roll 4. Said blocks 7—7 are adjustably held, by springs 8—8 and adjusting screws 9—9, to hold roll 6 against the outer periphery of sleeve 5 thereby forming a narrow throat 10 through which the material to be flaked must pass. A casing 11 encloses the pressure rolls and is provided with an intake opening 12 which is connected through a funnel 13 with a suitable supply of soy beans. A plate 14 is mounted adjacent the intake opening to insure proper feeding of the material through the throat 10. In order to prevent the flaked material from adhering to the surfaces of roll 4 and 5, I provide spring biased stripper fingers 15 and 16 mounted on a rod supported in the side walls of casing 11 and extending between the outer face of roll 4 and the inner face of sleeve 5 to cooperate with said roll and sleeve to remove all particles of material adhering thereto. A small spring-mounted roll 17 may be provided within the casing 11 to retain sleeve 55

5 in its proper relationship with plate 14 thereby preventing any beans from jumping over said plate and clogging the space above the stripper fingers. Any suitable means may be provided for 5 the discharge of flaked material from the sleeve 5 such as a conveyor, not shown, or by slightly inclining the axes of rolls 4 and 6 to provide a gravity discharge through a suitable opening 12' in the side of the casing 11.

10 A driving train, indicated generally at 18, is driven from a suitable source of power such as motor 19. The action of train 18 is to rotate pressure roll 6 in a counter-clockwise direction, as viewed in Fig. 1, while roll 4 has a clockwise 15 rotation. It is obvious that the opposite rotation of rolls 4 and 6 contacting sleeve 5 will result in a clockwise rotation of said sleeve thereby aiding the feeding of the beans through the throat 10, the size of which may readily be adjusted 20 through springs 8 and screws 9 to provide proper pressure for flaking, depending on the produce being fed into the machine.

The above-described machine is particularly applicable for use in flaking soy beans preparatory to passing said beans through the process 25 of extracting the oil therefrom with solvent or by any other suitable means.

As the result of the structure heretofore described, I am enabled to construct a machine 30 which may be extremely small in dimensions and simple to operate. I have found by experience that by the structure described, I am enabled to use rolls which need not exceed six inches in diameter, and that, even with the use of rolls 35 of small diameter, it is not necessary to, prior to feeding the soy beans into the flaking machine, cutting or macerating the beans so that they will pass through the rolls.

In certain types of apparatus heretofore used 40 for flaking or crushing soy beans, the use of extremely large rolls, twenty inches or more in diameter, has been found necessary and up until the development of my machine, so far as I am aware, it has not been feasible to crush or flake 45 soy beans in a machine using rolls smaller than twenty inches in diameter.

As a result of the above construction, I am enabled to materially simplify and cheapen the production of soy bean meal and oil.

50 Furthermore, it will be noted, from the above description, that it is unnecessary to provide any substantial supporting mechanism for the sleeve 5. Due to the fact that this sleeve is pressed against the roll 4 at the tangential juxtaposition point of the rolls 6 and 4, the pressure exerted

upon the sleeve at this point will maintain the sleeve in its relative position with respect to the roll 4.

I claim as my invention:

1. In a soy bean flaking machine, in combination, a pair of crusher rolls rotating in tangential juxtaposition with their axes in substantially the same horizontal plane, one of said rolls having a fixed axis of rotation and the other having a movable axis, independent spring means bearing upon the opposite ends of the shaft of said movable roll for resiliently biasing the movable roll toward the other with sufficient pressure to flake the beans without disintegrating the same and a sleeve of greater diameter than and surrounding said roll with the fixed axis of rotation and engaged by the other roll at said tangential juxtaposition point and movable relatively to said fixed axis roll and with said movable roll, said sleeve and rolls moving in a direction to feed 20 the beans from top to bottom.

2. In a soy bean flaking machine, in combina-

tion, a base, a pair of fixed bearings mounted on said base, a shaft mounted in said bearings and a crusher roll mounted on said shaft, a second pair of bearings mounted on said base, independent spring means for biasing each of said bearings toward said stationary bearings, a shaft operating in said bearings, a crusher roll mounted on said shaft and biased by said spring means into engaging relation with said first-mentioned roll with sufficient force to flake the beans without disintegrating the same, said shafts being substantially in the same horizontal plane, a sleeve of greater diameter than said first-mentioned roll and surrounding said roll and engaged by said second-mentioned roll at the tangential juxtaposition point of the two rolls, said sleeve being of the same longitudinal extent as the first-mentioned roll and movable with the second-mentioned roll relatively to the first-mentioned roll, and means for independently adjusting the tension of each of said spring means.

HARRY TRUAX.
